UNITED STATES PATENT OFFICE.

SALEM SMITH, OF DETROIT, MICHIGAN, ASSIGNOR TO FEDERAL MOGUL CORPORATION, OF DETROIT, MICHIGAN, A CORPORATION OF MICHIGAN.

AGITATOR FOR MOLTEN BABBITT AND THE LIKE.

Application filed December 30, 1927. Serial No. 243,554.

This invention relates to apparatus for effecting the mechanical agitation of molten Babbitt metal or similar material, in order to insure the greatest possible degree of uniformity in the mixture as removed by ladling or similar steps in the manufacturing operation, and has for its object an improved organization of parts by means of which the molten mass, composed of various metal components of diverse relative weight, may be kept substantially uniform from top to bottom and so that the heavier components, such as copper, will not tend to settle near the bottom of the melting vat, leaving an unduly light and not thoroughly commingled mixture near the top from which naturally the successive ladles full are manually removed by dipping. My invention also involves the provision of convenient means for lifting or swinging the agitating member out of the vat, when for any reason more unobstructed access thereto is desired, without involving the complete and time-wasting disassemblage of the parts, as well as the provision of means for protecting this agitating member from injury, due to the careless throwing into the vat of additional ingots of the various metals of which the molten mixture is composed.

In the drawings:

Figure 1 is a front elevational view of my improved mechanism shown in relation to the melting vat and to the preferred form of connection to a source of power.

Figure 2 is a side elevational view partly in section, and showing in dotted lines the raised or swung-up position of the agitating mechanism relatively to the vat.

Figure 3 is a plan view from above.

Figure 4 is a sectional detail, taken along the line 4-4 of Figure 2 and looking in the direction of the arrows there shown.

Figure 5 is a perspective of the preferred form of guard member, between whose parts the agitating member is held in suitable position.

12 represents a vat or melting pot, positioned subadjacently of a supporting frame 13, the upwardly extending portion of which is designed to support the rotatable shaft 14 whereon the pulleys 15 and 25 are mounted.

In Figure 1 I have shown two of these pulleys, one, as 25, being an idler over which the power belt 29 can be slipped from its otherwise actuating engagement over the

active pulley 15, when for any reason it is desired to temporarily halt the activity of the mechanism here described. Of course any desired or equivalent means for effecting the rotative movement of the shaft 14 could be substituted for this belt-driven means.

The right-hand end of the shaft 14, viewed from the position shown in Figure 1, is surrounded by the sleeve projection 16 of a fixed housing, in which is positioned, to rotate with the shaft 14, the bevel gear 17, whose teeth mesh with those of the companion gear 18 which is mounted upon the vertical shaft 19, which latter is rotatably held in position by the lower projection or sleeve 20 of the housing 16. This shaft 19 also engages rotatably in a box or housing 21, the rear end of which is pivoted, as at 22, in the frame or base 23, of which the already mentioned supporting bracket 13 is structurally a part. The shaft 19 continues below this housing to a point near the bottom of the vat or melting pot 12, and carries on its lower end the propeller or agitating blades 24, whose induced rotative movement in the mass of molten metal contained within the vat acts to keep in a state of agitation the fluid components of this mass and constantly disturb for remingling with the lighter components whose tendency is to rise to the top of the molten mass, such heavier component as copper, which would otherwise sink to the bottom of the vat. Access to the molten contents of the vat when the agitating mechanism is in the full-line position shown in Figure 2 may be had by ladling or any other desired method of removal.

When for any reason it is desirable to clear the vat of this agitating mechanism, this may be easily effected without disassemblage of the parts by swinging the whole vertical structure, of which the shaft 19 is the central feature, upwardly about the pivot 22 as a center, bringing it to the dotted line position shown in Figure 2, though I do not desire to be considered to restricting myself to the construction here shown, since, at the expense of the convenience thus afforded, this pivotal arrangement could be omitted in favor of a solid or permanent supporting means for the pivot 19. If such swinging construction is indulged in, it will of course be obvious that provision must be made for the release of the shaft 14 and its associated parts from its nor-

mal support in the top of the bracket 13. It is also desirable to effect the secure holding down of the hinged support for the shaft 14 so that it will be in permanently reliable vertical position by some such means as the pin 25, extending through the supporting arm or shell 21 and into a suitable portion of the framework 23, this being withdrawn from its interlocking position when the described 10 upward swing of the parts appurtenant the shaft 19 is desired.

While not indispensable to the operation of the mechanism thus far described, the protective means shown in Figures 4 and 5 for 15 the agitator blade and the lower end of its supporting shaft contributes appreciably both to the rapid operability of the device and to the duration of its possible use. The preferred form herein illustrated consists of 20 a specially formed block or framework which is attached at its top 30 by means of bolts or equivalent means to the under face of the supporting frame 13. This top is sufficiently deeply indented as at 31 to permit the rotative engagement through it of the blade-carrying shaft 19 and the depending skirting 32 on either side of the line of this indentation is similarly apertured lengthwise, in order to permit the swing through this space 25 of the shaft 19 when it is moved to the dotted line position shown in Figure 2. That portion of the skirting diametrically opposite from this lengthwise apertured part which, if present, would be shown in the left foreground of perspective Figure 5 is largely cut away, however, in order to give as free access as possible of the molten metal about the agitator blades. The depending skirtings 32 being located facing the front of the device and 30 of the vat or pot 12 from which direction the added metal ingots are usually deposited in the vat, their protective function proves in practice to be ample.

What I claim is:

- 45 1. Means for agitating molten babbitt and the like, having, in combination with a supporting frame adapted to be positioned over the open top of a container, a pivotally connected bracket supported therefrom, said 50 bracket having its end formed as a bearing of vertical axiality when the bracket is in lowered position, a shaft rotatably supported intermediate its ends by said bearing portion of said bracket, an agitating blade carried on the lower end of the shaft, and means carried on the upper end of the shaft whereby it may

have rotative actuation transmitted to it from an external power source.

2. In combination with a supporting frame, a vertically movable bracket member pivotally supported thereby, a rotatable shaft normally supported in vertical position intermediate its ends by said bracket member, and adapted to be swung with it to a position of axial obliquity thereover, an agitating 60 blade carried by the lower end of said rotatable shaft in position to act upon a fluid mass into which the shaft end is lowered, and means operatively engaging the upper end of said shaft for transmitting rotative actuation 65 thereto from an external power source. 70

3. In combination with a supporting frame, a vertically movable bracket hingedly supported thereby, a shaft provided with an agitating projection on its lower end, rotatably journaled therein intermediate its ends in normally vertical position, a guard member for the agitating lower end portion of the shaft supported from said movable bracket, and means for imparting actuation 75 to said shaft when in operative vertical position relatively to a subjacent fluid mass into which the lower end of said shaft normally extends. 80

4. The combination, with a bracket member pivotally supported in position for swinging in a vertical plane, of a shaft rotatably journaled in said bracket and extending appreciably on either side thereof, said shaft being adapted to swing with said bracket 85 out of its normally vertical position, an agitating member carried on the lower end of said shaft, and means operatively engageable with the top end of said shaft whereby it may be rotatively actuated from an external power 90 source. 95

5. In combination with a fixed base portion and a vertically swinging bracket member supported thereby, a shaft provided with an agitating blade on its lower end and having its intermediate portion, rotatably journaled in said bracket member, means supported upon said bracket whereby said shaft is rotatively actuated from an external power source, and means for shielding the blade on 100 the lower end of said shaft against the impact of foreign articles, though out of interfering position as regards the operative movement thereof. 105

In testimony whereof I sign this specifica- 110
tion.

SALEM SMITH.
